(57) CLAIM

The ornamental design for the clerical collar, as shown and described.

DESCRIPTION

FIG. 1 is a front perspective view of the clerical collar incorporating my new design;

FIG. 2 is a rear perspective view thereof;

FIG. 3 is a front view thereof;

FIG. 4 is a rear view thereof;

FIG. 5 is a left end view thereof;

FIG. 6 is a right end view thereof;

FIG. 7 is a bottom plan view thereof; and,

FIG. 8 is a top view thereof.

The broken lines illustrate portions of the clerical collar that form no part of the claimed design.
